UNITED STATES PATENT OFFICE.

HILLIARY ELDRIDGE, OF OAKLAND, CALIFORNIA, ASSIGNOR, BY MESNE ASSIGNMENTS, AND COURT ORDER, TO MARTHA K. ELDRIDGE.

ELECTRIC FURNACE.

Application filed May 19, 1925. Serial No. 31,391.

The present invention relates to improvements in an apparatus for and a process of producing calcium carbide, and its principal object is to provide an improved furnace for producing calcium carbide from a mixture of lime and carbon which, at the same time has features embodied therein which allow the waste heat as well as the products of combustion to be utilized for treating other materials, such as shale, so that liquid hydrocarbons may be gained from the shale as a by-product in the process of manufacturing calcium carbide. This latter feature is all the more advantageous because shale can ordinarily not be turned into liquid hydrocarbons at an advantage due to the high cost of fuel, while in my improved apparatus there is practically no extra expense connected with the treatment of the shale while, furthermore, after treatment there remains a residue of carbon which can be used as one of the constituents of calcium carbide.

When subjecting a mixture of lime and carbon to an electric arc, carbon monoxide is released, and it is the object of my invention to not only utilize the heat radiated from the furnace for heating retorts containing shale, but to also inject a supporter of combustion, such as atmospheric air, into the carbon monoxide so as to allow the same to combust and give additional heat while passing the retorts containing the shale.

For a convenient arrangement a plurality of retorts may be provided some of which may be filled with shale while others may be filled with coal for the production of coal gas which may be utilized in calcining lime stone for the production of lime, the other constituent of calcium carbide, so that where my improved process and apparatus are employed, calcium carbide and liquid hydrocarbons may be rapidly and cheaply produced in a single combination process wherever a deposit of lime stone and of shale is available, in addition to a limited amount of coal.

In addition to the general arrangement of my apparatus for the purposes set forth hereinabove, I provide specific features which render my apparatus particularly adapted to perform its functions and for easy handling of the materials employed.

The preferred form of my apparatus is shown in the accompanying drawings, in which

Figure 1 shows a vertical section through the same.

Figure 2 a horizontal section taken along line 2—2 of Figure 1.

Figure 3 a horizontal section taken substantially along line 3—3 of Figure 1.

Figure 4 a sectional detail view taken along line 4—4 of Figure 1.

Figure 5 a vertical section through a modified form of furnace, and

Figure 6 a horizontal section taken along line 6—6 of Figure 5.

While I have shown only the preferred forms of my invention, I wish to have it understood that various changes or modifications may be made within the scope of the claims hereto attached without departing from the spirit of the invention.

My furnace as illustrated in Figures 1 to 4 includes as its principal parts an elevated side wall structure 11 made of refractory material and resting on any suitable frame 12 leaving the space below the side structure clear to accommodate the portable bottom 13 of the furnace. The latter comprises a truck 14 adapted to ride on the rails 16 having a central projection 17 rising therefrom and the body 18 of the bottom which is formed with a central cavity 19 and has a sleeve 21 depending therefrom which telescopes over the projection 17 while a shaft 22 is threaded into the projection and bears through balls 23 on the underface of the body of the furnace bottom so that the latter may be raised and lowered at will by turning the shaft 22, the turning motion being executed by means of a handle 24.

It will be seen that in this manner the body of the bottom can be brought in intimate contact with the stationary side wall structure by raising the body, the top edge of the latter fitting into an annular flange 26 depending from the platform 27 on which the side wall structure rests and the opening of the cavity at the top being coextensive with the opening in the side wall structure.

At the top the side wall structure is closed by means of a plurality of blocks 27 of insulating material held in place by a metal ring 28 surrounding the same, which latter is bolted as shown at 29 to a supporting plate 31 resting on the side wall structure, while the blocks 27 rest on ledges 32 formed in the refractory material and are confined at the

top by angle irons 33. Centrally supported with freedom of sliding motion in the top members 27 is a carbon electrode 34, the lower end of which extends into the cavity of the bottom 13, and the lower blocks 27 are recessed around the carbon electrode as shown at 36 to allow material to be fed into the furnace from the hopper 37 through the pipe 38 by means of the conveyor 39 which is driven 10 from the motor 41. The carbon electrode 34 is supported in the clamp illustrated in detail in Figure 3, consisting of a horizontal arm 42 recessed near its free end as shown at 43 to encompass a peripheral section of the 15 carbon electrode and a second arm 44 similarly recessed as shown at 46 to encompass an opposing section of the carbon electrode, while two screws 47 extending through the arm 44 and threaded into the arm 42 clamp 20 the two arms together, the projecting lug 48 of the arm 42 engaging with the face of the arm 44 for maintaining the two arms in substantially parallel relation. Each of the arms is provided with a water cooled chamber 49 25 adjacent the carbon electrode through which water may be passed through the pipes 51 and 52.

The arm 42 is supported to always maintain a horizontal position but with freedom of 30 vertical adjustability by riding on two vertical shafts 53 spaced from one another and rising from an insulating block 45 secured to the top plate 31 while motion may be imparted to the arm through the threaded rod 35 56 engaging the same as at 57 which latter rod has a gear wheel 59 keyed thereto as shown at 61 with a worm 62, illustrated in Figure 4, imparting rotary motion to the gear wheel 59 when the handle 63 is manually 40 revolved.

The carbon electrode 34 extends into the cavity of the bottom portion 13 while a second electrode 64 is supported in the body of the removable bottom section. The latter is 45 for this purpose provided with a port 66 which may serve as a discharge port for the treated material and which is closed by the insertion of the carbon electrode, both port and electrode being preferably tapered in a 50 manner illustrated in Figure 1, and the electrode being forced into place through the water cooled conducting element 67 which has the head 68 of the pin 69 threaded thereinto and which is advanced by means of a nut 55 71 in the frame 72, the nut being separated from the conducting element 67 and the pin 69 by means of two insulators 73 and 74. A wire 76 is secured to the pin 69 as shown at 77 and the other line wire 78 is secured to the 60 arm 42 as shown at 79. The frame 72 is preferably pivotally secured to stationary brackets 81 extending from the body of the portable bottom as shown at 82 so that when it is desired to remove the carbon electrode, it is 65 only necessary to loosen the nut 71 and to turn

the frame 72 on its hinge whereupon the carbon electrode may be pulled out.

The stationary refractory side wall of the furnace is preferably built to present in horizontal section a plurality of wings 83 each 70 of which is recessed radially relative to the furnace proper as shown at 84 and accommodates in the recess a retort 86 accessible from the outside by removal of the cover 87 clamped upon its open end by means of a 75 screw 88 threaded into a yoke 89 braced against the inner face of a flange 91. Each recess communicates at its outer end with a flue 92 through which the products of combustion from the furnace may escape. Each 80 of the recesses also has a pipe 93 preferably made of porcelain leading thereinto in such a manner that air forced through the pipe by means of a pump not shown in the drawing is discharged in the recess in the direction of 85 travel of the products of combustion at the inner end of the retort, as shown at 94. The retorts are provided with suitable outlet pipes 96 which lead to a suitable condenser, preferably of fractional condenser type. 90

The operation of the device may be described as follows:

A mixture of lime and carbon is fed into the hopper 33 and is conveyed through the pipe 38 into the bottom cavity 19. An arc 95 formed between the two electrodes converts the mixture into calcium carbide and during the process carbon monoxide is released as one of the products of the combustion. Heat is radiated from the furnace and passes 100 through the recesses 84 and past the retorts 86 into the flues 92. Before the gases forming the product of combustion in the furnace pass the retort, air is forced into the same and allows the carbon monoxide to be combusted 105 to provide additional heat units for the retorts 86.

Any desired number of retorts may be provided and I preferably use most of them for the distillation of shale, the retorts being filled 110 with shale at suitable intervals and the heat serving to distill hydro-carbon gases from the solid material which gases may be guided through the pipe 96 into a fractional condenser 115 for the production of oils of various degrees. As a residue, carbon remains in the retort and may be utilized either for the manufacture of carbon electrodes or for mixture with lime in the hopper 37 for production of calcium carbide. One of the retorts is preferably used for distillation of coal for the production of coal gas and hydro-carbon vapors 120 adapted to be utilized in the calcining of calcium carbonate into lime which forms the other constituent of the calcium carbide, 125 while the carbon resulting from the distillation of the coal may also be used as a constituent of the calcium carbide.

When the process is completed relative to one batch of calcium carbide, the bottom 13 130

may be lowered, the truck pushed forward after the vertical carbon electrode 34 has been raised and a new truck and bottom may be substituted whereupon the process may be continued immediately. After the truck has been removed, the nut 71 may be unscrewed whereby the conducting element 67 is separated from the carbon electrode 64 which allows the frame 72 to be turned on its hinge 10 and the carbon electrode 64 to be removed so as to establish an outlet for the contents of the cavity.

In Figures 5 and 6 is shown a slightly different arrangement which follows substantially the same principle, the difference consisting in a slightly different arrangement of the retorts and in the provision of a plurality of carbon electrodes. In this type the furnace is preferably made rectangular and the bottom 97 is trough-shaped so that a plurality of horizontal electrodes 98 may be introduced through the side thereof while a similar plurality of vertical electrodes 99 are arranged in a manner similar to that shown in Figure 25 1. The retorts 101 instead of radiating from a common center are arranged parallel to the sides of the rectangular furnace in recesses 102 provided for the same with flues 103 communicating with the recesses at their 30 upper ends. A charge is delivered into the furnace through the pipe 104 in a manner similar to that previously described. The retorts may be arranged so that they may be opened at either end as shown at 106 in Figure 35 6.

In addition to supporting the combustion of the carbon monoxide gas, the current of atmospheric air traveling under the retort in the direction of the furnace outlets creates 40 a pull or suction on the carbon monoxide gas as it is produced in the calcium carbide reaction, with the result that the pressure of the reaction is kept reduced to a minimum and an increased production of calcium carbide is accomplished through the fact that the 45 reaction proceeds continuously for reverse reaction cannot take place if an equilibrium of pressure is prevented by constant exhaustion of pressure.

50 While in the preceding description reference is had to the manufacture of calcium carbide, the outstanding features of my process and of my apparatus may be used to the same

advantage in the manufacture of aluminum and cast steel or iron.

55

I claim:

1. In an electric furnace of the character described, a stationary side wall structure having an electrode extending thereinto, a portable bottom formed with a central cavity having means for raising the side walls thereof into intimate contact with the stationary side wall associated therewith and being formed with a discharge port communicating with the cavity and a second electrode normally disposed in the discharge port for closing the same.

2. In an electric furnace of the character described, a stationary side wall structure having an electrode extending thereinto, a portable bottom formed with a central cavity having means for raising the side walls thereof into intimate contact with the stationary side wall associated therewith and being formed with a tapered discharge port communicating with the cavity, and a tapered electrode adapted to close the discharge port having means connected therewith for positively driving the same into the exhaust port.

3. In an electric furnace of the character described, a stationary elevated side wall structure, a portable furnace bottom having means for raising the same into intimate contact with the side wall structure associated therewith, means for feeding material through the side wall structure into the bottom, electrodes arranged to provide a gap within the said bottom, and retorts arranged in the side walls of the stationary structure so as to cause products of combustion to pass the same.

4. In an electric furnace of the character described, a stationary elevated side wall structure, a portable furnace bottom having means for raising the same into intimate contact with the side wall structure associated therewith, means for feeding material through the side wall structure into the bottom, electrodes arranged to provide a gap within the said bottom, and retorts arranged in the side walls of the stationary structure so as to cause products of combustion to pass the same with means for forcing a combustion supporter into the said products of combustion before they strike the retort.

HILLIARY ELDRIDGE.
